(57) **CLAIM**

The ornamental design for a rocker arm for engine brake, as shown and described.

DESCRIPTION

FIG. 1 is a perspective view of a rocker arm for engine brake showing the new design.

FIG. 2 is a first side view of the rocker arm for engine brake of FIG. 1.

FIG. 3 is a second side view of the rocker arm for engine brake of FIG. 1.

FIG. 4 is a front view of the rocker arm for engine brake of FIG. 1.

FIG. 5 is a rear view of the rocker arm for engine brake of FIG. 1.

FIG. 6 is a top view of the rocker arm for engine brake of FIG. 1; and,

FIG. 7 is a bottom view of the rocker arm for engine brake of FIG. 1.

Any portion of the rocker arm for engine brake shown in broken lines is for the purpose of illustrating environmental structure and forms no part of the claimed design.
